(57) **CLAIM**

The ornamental design for a decorative lamp, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top-front-left perspective view of a decorative lamp showing my new design;

FIG. 2 is a bottom-rear-right perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a front elevational view of a second embodiment of a decorative lamp shown broken away, that being the only difference from the embodiment shown in FIGS. 1 through 8.

The broken lines shown in drawings are included for the purpose of illustrating portions of the lighting device, and form no part of the claimed design.
